UNITED STATES PATENT OFFICE.

CHARLES W. JEAN, OF NEW YORK, N. Y.

COPYING-MACHINE.

1,281,782.

Specification of Letters Patent. Patented Oct. 15, 1918.

Application filed May 20, 1915, Serial No. 29,414. Renewed January 23, 1917. Serial No. 144,058.

To all whom it may concern:

Be it known that I, CHARLES W. JEAN, a citizen of the United States, residing at New York, in the county of New York and 5 State of New York, have invented certain new and useful Improvements in Copying-Machines; and do hereby declare the following to be a full, clear, and exact description of the invention, such as will enable others 10 skilled in the art to which it appertains to make and use the same.

This invention relates to presses, and more particularly to those employed for copying as from a typewritten letter; and the object 15 of the same is to produce a machine of this kind in which the day's letters may be rapidly copied onto a web of moistened tissue, the same then dried, and finally the dried web cut in standard lengths corresponding to that of the letters and each 20 duplicate sheet of tissue perforated with holes for binding by means of the prevailing system.

The machine includes an upright power 25 shaft which is rotated constantly by a prime mover such as an electric motor, when the current is turned on; a master shaft, and a clutch between it and the power shaft; moistening, wringing, pressing, and feeding mechanisms whereof each includes a pair of rollers and one of which is positively driven from the master shaft so that the tissue web whether wet or dry will be moved always at a uniform speed. a timing mechanism also driven from said master shaft; a manually controlled mechanism for simultaneously closing the clutch and releasing the timer, so that when the latter makes a complete revolution it automatically 35 releases the clutch; a drying mechanism between the presser rollers and the feeder rollers, and a cutting mechanism connected with said manual control—all as herein-after more fully described and claimed, and 40 as shown in the drawings in which:

Figure 1 is a side elevation of the device constructed in accordance with this invention,

Fig. 2 is a vertical sectional view there- 50 through, showing parts in elevation,

Fig. 3 is a side elevation of a portion of the machine from the opposite side from that shown in Fig. 1,

Fig. 4 is a vertical sectional view as on 55 the line 4—4 of Fig. 1, and

Fig. 5 is a perspective view of a portion of the machine showing the perforating and cutting mechanism.

In the use of tissue paper to receive a copy impression thereon in a moist state, it 60 is necessary that certain provisions be made for the handling of the tissue web in the most efficient manner to prevent tearing and also to reduce the lengths of moist areas to a minimum as well as to provide a universal 65 movement of all the parts of the web.

Referring to the drawings in which similar reference numerals indicate similar parts throughout the several views, there is shown a stand comprising the legs 10, cross bars 70 11 and fittings 12 on the upper portion thereof, which fittings are connected by the cross piece 13 to form a rigid structure. Bearings 14 are provided upon some of the bars 11 to support a roll of paper 15 having 75 the usual tension device 16 which may be adjustable to meet the requirements. From the roll 15 the web 17 passes over a roller 18 journaled in bearings of a frame 19 from where it passes between the moisten- 80 ing rollers 20 and 21 which are also supported by bearings in the frame. The latter has a reservoir for a quantity of water to moisten a fabric covering upon the roller 20 so that as the web 17 passes between the 85 rollers 20 and 21, it is moistened to the desired degree. After leaving the roller 21, the web passes between the wring- 90 g rollers 22 and 23 journaled in brackets 24 which are attached to vertical standards 25 rising 95 from the cross piece 12. The roller 23 is movably mounted in the brackets 24 and is held in engagement with the roller 22 under normal conditions by the compression spring 26, but when so desired, is moved 95 from engagement with the roller 22 by the thumb nuts 27 on the screw eyes 28 which support the trunnions for said roller and also pass through extensions on the brackets 24. In passing between the rollers 22 and 100 23, the surplus water is removed from the web and the degree of moisture may be controlled by manipulation of the wing nuts 27.

After passing from the roller 22, the web passes between the pressing rollers 29 and 105 30 of which the roller 29 is journaled in fixed bearings carried by the standard 25 and the roller 30 is movably mounted, being carried by the ends of the levers 31 which are pivoted as at 32 to the standards and from 110

which extend the arms 33 to support a handle 34. Movement of the handle 34 varies the contact of the rollers 29 and 30 upon the web 17 and likewise creates the impression upon the web 17 as a letter written with the ordinary copying ink is also passed between rollers 29 and 30. Thumb screws 35 are carried by the brackets 36 to establish the desired compression between the rollers 29 and 30 by releasing or depressing the arms 33 as the case may be.

After leaving the rollers 29 and 30 and having the impression made thereon, the web passes to a drying cylinder or drum 37 in which a gas or other heater 38 is mounted and to cause the desired contact of said web with the drum 37, a roller 39 bears upon the drum 37 from above, while a roller 40 engages the lower portion of said drum so that the paper binds against said drum for the major portion of its circumference. The rollers 37, 39 and 40 are journaled in standards 41 which are also formed on the cross pieces 12 and roller 39 is removably mounted in the upper end of said standards.

Upon leaving the roller 40, the web passes to the feeding rollers 42 and 43 which are journaled in brackets 44 carried by the legs of the frame and the roller 43 is adjustably mounted so that the compression spring 45 may bind the roller 43 against the roller 42. Like the roller 23, the roller 43 has its trunnions mounted in screw eyes 46 which receive the wing nuts 47 after passing through lugs 48 of the brackets 44. These feeding rollers advance the web to a perforating and cutting device which comprises a fixed blade 49 carried by the frame and a movable blade 50 which is pivoted as at 51 in a hub carried by the support for the blade 49. The cutting members 49 and 50 support perforating members comprising the plate 52 in which the punches 53 are set and the plate 54 in which holes 55 are formed to co-act with the punches 53 in perforating the end of each individual sheet formed from the web by the cutters 49 and 50. As tissue paper is difficult to handle satisfactorily, a movable plate 56 is provided through which the punches 53 pass and this plate is supported as by pins 57 passing loosely through the plate 52 and having compression springs 58 thereabout, to normally move the plate 56 beyond the ends of the punches 53 so that after the ends of the sheets are perforated and the blade 50 swung to the position shown in Fig. 5, the plate 56 removes the end of the web from about the punches 53.

A motor or other prime mover 59, is mounted upon a motor board 60 which in turn is carried by some of the cross bars 11 and this motor has a worm 61 on the shaft thereof, which meshes with the worm gear 62 carried by an upright power shaft 63.

The shaft 63 has its lower end journaled in a bearing 64 and its upper end in a sleeve 65 which sleeve is journaled in the bearing 66 and said shaft has a clutch member 67 splined thereon to permit sliding movement 70 of said clutch for engagement with a clutch 68 formed on the sleeve 65. The sleeve 65 supports a beveled pinion 69 which meshes with the beveled gear 70 carried by the shaft of the roller 29. The opposite end of this, 75 which might be called the "master" shaft, M carries the spur gear 71 which through the idler 72 drives the gear 73 on a timing shaft 74; and in addition to the spur gear 71, the master shaft M also carries a beveled gear 80 75 with which the pinions 76, 77 and 78 carried by the shafts 79, 80 and 81 respectively, engage to impart motion to the several shafts. The rollers 22, 20 and 42 have beveled gears 82, 83 and 84 respectively, carried 85 by the ends of the shafts of said rollers and these gears mesh with pinions 85, 86 and 87 respectively carried by the shaft 79, 80 and 81. It is seen that as the master shaft M is rotated by the motor 59, the rollers 20, 22, 29 90 and 42 are driven at a uniform speed so that the paper contacting with these rollers in the order named, moves uniformly throughout its length without fullness or slack and without wrinkling or tearing, even though 95 it be moist.

While in operation, the armature of the motor 59 and the power shaft 63 run continuously and when it is desired to make a letter copy, the clutch members 67 and 68 are brought into engagement, but as soon as the predetermined length of the web 17 is passed between the pressing rollers 29 and 30 to receive the impression, the clutch members 67 and 68 are automatically disconnected until 100 such connection is reestablished periodically to advance the copy to the cutters 49 and 50 which in ordinary usage would be by the continued operation of copying letters. This clutch mechanism is closed by a manually 105 operated lever and held closed for a certain period by a timing mechanism described in the following manner: A treadle 88 pivoted as at 89 to one of the legs of the stand has a pin 90 which works in a slot 91 formed in the lower end of a lever 92 which is fulcrumed as at 93 to one of the cross bars 11. The upper end of the lever 92 passes through an opening in the slidable bar 94 which is carried in a guide 95 having the slots 96 and 97 formed therein to permit freedom of movement of the lever 92 and the lower end of the arm 98. This arm extends from a hub 99 which is pivoted as at 100 to a bracket 101 and the hub 99 has the teeth 102 formed thereon for engagement with the segment 103 carried by the pendent arm 104 of a bell-crank lever. The other arm 105 of such lever has a toothed segment formed thereon for engagement with the rack 106 formed on 120 105 110 115 120 125 130

one arm 107 of an inverted U-shaped yoke. The bell-crank lever comprising the arms 104 and 105 is fulcrumed as at 108 to a bracket carried by one of the cross bars 11. The yoke-arm 107 carries a fork 109 to engage the clutch member 67 so that as the arm 107 is raised, the clutch member 67 is likewise raised and when the treadle 88 has been depressed through the mechanism just described, the clutch members 67 and 68 are thrown into engagement. To hold said clutch members in engagement for a given time, a timing wheel 110 is attached to one of the ends of the shaft 74 and this wheel has a notch 111 in its periphery to receive a roller 112 carried by the bend of said yoke. Beyond such bend the yoke is continued downward in a second arm 113 which is maintained in vertical position by having the lower end thereof pass between the guides 114 carried by one of the cross bars 11. In the action of the parts just described, when the operator depresses the treadle 88 motion is communicated to the bell-crank lever, the latter lifts the yoke, and the rise of the yoke causes its fork 109 to throw the clutch members into engagement. The various parts of the machine then immediately begin their movements, and the timing wheel 110 commences to rotate, as the rise of the yoke has lifted the roller 112 out of the notch 111. The removal of pressure from the treadle permits the yoke to drop back part way, but it is checked by the roller 112 resting on the periphery of the wheel 110. The circumference of the latter is equal to the length of the standard letter sheet, and therefore during the revolution of the timing wheel just that much of the tissue web is drawn through the machine. As soon as said wheel has made one complete revolution the roller falls again into the notch 111 which permits the yoke to drop back to its original position and as it does so the fork 109 disengages the clutch members so that all parts of the machine except the motor and power shaft come to rest again. The removal of pressure from the treadle and the retraction of the bar 94 also actuate the cutting mechanism which severs a standard length from the rear end of the web and punches holes above the line of cut so that they will be at the top of the tissue sheet next to be cut from the web when the operation is repeated.

The end of the sliding bar 94 is connected as by the arm 115 to the rock shaft 116, journaled in the sleeve 117, and said rock shaft has an arm 118 which is connected as by a link 119 to an arm 120 formed on the lower end of the pivot for the cutter blade 50 so that manipulation of the treadle to set the mechanism into operation also serves to separate the cutter members which are brought into operation to sever the sheet

from the end of the web as soon as the timing wheel 110 has made a revolution. The perforating mechanism co-operates with the cutting mechanism as is clearly understood.

The table 121 is provided to assist in feeding the letters to be copied between the roller 29 and 30 and a basket 122 may be provided to receive the copies as cut from the web by the cutters 49 and 50.

The segment 105 may be connected as by a spring 123 to the guide 95 to positively return the several parts actuated by the bar 94 to a normal position.

Various modifications may be made within the scope of this invention without departing from the spirit thereof, and the drawings are submitted for illustrative purposes only.

Having thus described my invention, I claim:—

1. In a copying machine, the combination with a frame, and a drying roller journaled so as to run free in bearings carried by the frame; of moistening, wringing, pressing, and feeding mechanisms whereof each comprises a pair of rollers journaled in said frame with the feeding mechanism behind and the other mechanisms forward of said drier, a master shaft, and positive connections between it and the shaft of one roller in each of said mechanisms whereby all are driven at the same speed.

2. In a copying machine, the combination with a frame, and a drying roller journaled so as to run free in bearings carried by the frame; of moistening, pressing, and feeding mechanisms whereof each comprises a pair of rollers journaled in said frame with the feeding mechanism behind and the other mechanisms forward of said drier, a master shaft fast through one roller of the pressing mechanism, and positive connections between said shaft and that of one roller in each of the other mechanisms whereby all the latter are driven at the same speed.

3. In a copying machine, the combination with a frame, two pairs of standards mounted therein, and a drier comprising a heated drum and idle rollers above and beneath, all journaled in the rearmost standards; of pressing mechanism including a master shaft journaled in the forward standards and having a roller and a manually adjustable roller adjacent to it, a pair of moistening rollers forward of said pressing mechanism, a pair of feeding rollers rearward of said drying mechanism, direct and positive connections between said master shaft and one roller in each of said pairs whereby all rollers are rotated at the same speed, and means for controlling the rotation of the master shaft.

4. In a copying machine, the combination with a master shaft, pressing mechanism directly carried thereby, moistening and feed-

ing mechanisms, and means for driving them positively from the master shaft; of a timing shaft, a wheel thereon having a notch in its periphery, direct connections between this 5 shaft and the master shaft, a power shaft, clutch mechanism between it and the master shaft, a member having a fork engaging said clutch and a projection engaging said notch, and manually operable means for moving 10 said member to simultaneously close the clutch and disengage the projection from the notch, for the purpose set forth.

5. In a copying machine, the combination with a master shaft, pressing mechanism directly carried thereby, moistening and feeding mechanisms, and means for driving them positively from the master shaft; of a timing shaft, a wheel thereon having a notch in its periphery, direct connections between this 15 shaft and the master shaft, a power shaft, clutch mechanism between it and the master shaft, a yoke extending over said timing wheel and having a roller adapted to engage the notch therein, a fork on the yoke engaging one element of said clutch, a treadle, and connections between it and said yoke for raising the latter whereby the clutch is closed and the roller disengaged from said notch simultaneously, for the purpose set 20 forth.

6. In a copying machine, the combination with a master shaft, pressing mechanism directly carried thereby, moistening and feeding mechanisms, and means for driving them positively from the master shaft; of a timing shaft, a wheel thereon having a notch in its periphery, direct connections between this shaft and the master shaft, a power 25 shaft, clutch mechanism between it and the master shaft, a yoke of inverted U-shape whose bend overlies said timing wheel, a roller carried within the bend and adapted to engage the notch in the wheel or to ride on its periphery, a guide for one yoke-arm, a fork on the other arm engaging one 30 clutch member, a treadle, and connections between it and the yoke for raising the latter to close the clutch members and disengage the rollers from the notch whereby the timing wheel is freed, said roller adapted to 35 reengage the notch when the wheel has made a complete revolution, whereby the yoke descends and automatically opens the clutch.

7. In a copying machine, the combination with tissue paper web-handling devices including moistening, pressing, drying, and feeding mechanisms, a master shaft rotating in timed relation with the pressing mechanism, a timing shaft geared to the master 40 shaft, and a timing wheel on said timing shaft provided with a notch in its periphery; of an inverted U-shaped yoke overlying said wheel, a roller in its bend adapted to drop into said notch, means for manually 45 raising said yoke to disengage the roller

from the notch, and devices actuated by the rise of the yoke to connect said master shaft with a source of power whereby a standard length of the tissue paper web will be passed through the pressing mechanism and then its 50 action automatically checked.

8. In a copying machine, the combination with tissue paper web-handling devices including moistening, pressing, drying, and feeding mechanisms, a master shaft rotating 55 in timed relation with the pressing mechanism, a timing shaft geared to the master shaft, and a timing wheel on said timing shaft provided with a notch in its periphery; of a member having a projection adapted to engage said notch, devices carried by said member for connecting the master shaft with a source of power when the projection is disengaged from the notch, treadle mechanism for actuating said member, web-cutting 60 blades beyond said feeding mechanism, and connections between such blades and treadle mechanism whereby the web is cut when the projection enters the notch and the progress of the web through the machine is interrupted.

9. In a copying machine, a drying surface, means to heat the drying surface, means to move a sheet of paper upon the drying surface and maintain such sheet in taut condition, means to apply moisture to the sheet before reaching the drying surface, and means to bring a document to be copied into contact with the sheet under pressure between the point of application of the moisture 65 and the heating surface.

10. In a copying machine, a moving drying surface, means to maintain the drying surface in heated condition, means to move a sheet of paper upon such drying surface at a speed coinciding with the movement of the drying surface and to maintain the sheet in taut condition, means to apply moisture to the sheet before reaching the drying surface, and means to exert pressure upon a document placed upon the sheet between the point of application of the moisture and the 70 drying surface.

11. In a copying machine, a moving drying surface, means to heat the drying surface, means to pass a sheet of paper along and in engagement with the drying surface at a speed coinciding with the movement of the drying surface, means to apply moisture to the sheet before reaching the drying surface, and means to impress a document to be copied upon the drying sheet intermediate the point of application of moisture and the 75 drying surface.

12. In a copying machine, a roller, means to heat the periphery of the roller, means to move a sheet about the roller at a speed corresponding to the movement of the periphery of the roller, means to apply moisture to the sheet before reaching the roller, and 80

means to impress a document to be copied upon the sheet between the point of application of the moisture and the roller.

13. In a copying machine, a drying surface, means to move a sheet of paper to bring portions of such paper into contact with the drying surface, means to apply moisture to the sheet before reaching the drying surface, and means to impress a document to be copied upon the sheet intermediate the moistening and the drying surface.

14. In a copying machine, a roller, a heating element within the roller adapted to heat the roller from within, means to move a sheet

about the roller at a speed corresponding to 15 the movement of the periphery of the roller, means to apply moisture to the sheet before reaching the roller, and means to impress the document to be copied upon the sheet between the point of application of the moisture and the roller. 20

In testimony whereof he affixes his signature in presence of two witnesses.

CHARLES W. JEAN.
